(Cl. D26—14)

FIG. 3.

FIG. 5.

FIG. 6.

FIG. 4.

Figure 1 is a front perspective view of a loud-speaker, showing my new design with the two relatively movable members in one position;

Figure 2 is a fragmentary side elevational view, a portion of the upper member being omitted for convenience in illustration;

Figure 4 is a fragmentary top plan view, a portion of the upper member being omitted for convenience in illustration;

forated grille extending across the entire fronts of the upper and lower members; and

I claim:

The ornamental design for a loud-speaker, substantially as shown and described.
